UNITED STATES PATENT OFFICE.

CHARLES A. MELCHERT, OF KANSAS CITY, MISSOURI.

VENDING-MACHINE.

1,098,582.

Specification of Letters Patent.

Patented June 2, 1914.

Application filed November 14, 1912. Serial No. 731,406.

To all whom it may concern:

Be it known that I, CHARLES A. MELCHERT, a citizen of the United States, residing at Kansas City, in the county of Jackson and State of Missouri, have invented certain new and useful Improvements in Vending-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to vending machines, and more particularly to a device for automatically vending toilet articles, or the like, when a suitable releasing trigger is actuated following the insertion of a coin through a slot in the casing of a machine.

More particularly the machine comprises a drum which is adapted for carrying a plurality of articles over a trap, and mechanism for stopping the drum and releasing the trap to deliver a single article to a purchaser.

In accomplishing the above objects I have provided the improved details of structure hereinafter described and illustrated in the accompanying drawings, wherein:

Figure I is a perspective view of a vending machine constructed according to my invention. Fig. II is a central, vertical section of same. Fig. III is a detail perspective of the storage drum. Fig. IV is a similar view of the trap plate. Fig. V is a detail perspective of the pointer and latch for stopping the storage drum in a vending position. Fig. VI is a side elevation of the trap plate and actuating mechanism. Fig. VII is a view of the same parts taken from the opposite direction. Fig. VIII is a rear view of the actuating mechanism. Fig. IX is a detail perspective of the rear portion of the mechanism looking downwardly into the rear end of the coin chute. Fig. X is a similar view of the opposite side of the parts shown in Fig. IX. Fig. XI is an enlarged, vertical section of the vending trap showing its relation to its plate. Fig. XII is an enlarged bottom plan view of the trap. Fig. XIII is a detail perspective of the delivery chute. Fig. XIV is a horizontal section of part of the coin chute showing the detector.

Referring more in detail to the parts, 1 designates a casing, which may be constructed of cast metal, and has a flat rear end 2 adapted to seat flush against the wall 60 of a room or hallway in a building, to which it may be secured by screws 3, or the like; the upper forward portion of the casing being extended as an overhanging shelf 4, the curved front face of which is provided with an opening 5 which may be closed by a door 6 having a lock 7. The upper portion of the casing has an inturned flange 8 surrounding a central opening 9, and seated on said flange and covering the opening is a trap plate 10. Seated on the edge of the trap plate is a glass globe 11 having an outturned flange 12 at its lower edge by means of which it is secured to the casing through its locking combination 75 with a rim 13 and screws 14, which latter extend up through the casing flange into lugs 15 on the inner surface of the rim. Journaled in the trap plate 10, and in a bearing 16 in the top of the globe, is a 80 spindle 17 having a handwheel 18 exposed above the top of the globe.

Fixed to the spindle within the globe is a drum comprising a lower plate 19 which is spaced from the trap plate 10 by a collar 85 20, and an upper plate 21 which is spaced from the lower member by studs 22 sufficiently to hold articles in vertical position within the drum.

The drum members are provided with 90 registering apertures 23, and opening inwardly from the apertures in the lower member are slots 24, for a purpose presently described.

The trap plate 10 is preferably provided 95 with edge notches 25 adapted for receiving the rim lugs 15, to hold the plate rigidly in position, and is provided with openings 26 and 27 of slightly greater diameter than the registering apertures 23 in the drum 100 members, the two openings being preferably arranged at about a ninety degree angle in order to facilitate the supplying of the machine, as presently described, and one of the openings being arranged near the 105 rim of the plate and in line extending diametrically through the plate from the front thereof.

Rising from the plate, at the front of the machine, but at the side of the diametrical line within which the trap opening is located, is an upturned pointer 29 having

an inturned spring lip 30 thereon adapted for wiping the edge of the lower drum member 19 and for seating in sockets 31 therein, to yieldingly hold the drum in position 5 when a pair of the registering openings are directly over the trap openings 26.

On the upper drum member, directly above the sockets 31, are pointers 33 and above the pointers are holders 34 which are 10 adapted for holding cards 35 upon which the name of an article carried in the drum may be marked, the name in the marker indicating the can of the other receptacle, or article, which is in the portion of the drum 15 directly over the trap opening 26 when the pointers 33 and 29 are in alinement.

The opening 26 in the trap plate is normally closed by a trap 37, comprising a round, metal cap which is adapted for projection into the opening and has a peripheral flange 38 adapted to underlie the plate and limit the upper projection of the cap, the trap being provided with a forwardly projecting ear 39 having hinged mounting 25 on a pin 40 carried beneath the trap plate.

Pivottally connected with the bottom of the trap 37 is a toggle link 43 which extends forwardly and downwardly and is pivotally connected with the main link 44, 30 which latter is in turn pivotally mounted on a pin 45 (Fig. VI) on the lower end of the coin chute 47 and has a stop head 48 projected into the chute channel and also provided with a tooth 49 which is adapted for 35 engagement with a finger 50 on a lever 51 which is also pivotally mounted on said chute.

Projecting laterally from the side of the toggle link 44 is a pin 52 which normally 40 engages the inclined edge 53 of the head 54 on the arm 55 of a bell crank lever 56, which is also pivotally mounted on the coin chute and has an arm 57 projected upwardly and pivotally connected with a plunger 58 45 which extends forwardly through an aperture 59 in the front of the casing.

The outer arm 55 of the bell crank lever 56 is normally yieldingly retained in an elevated position by a spring 60 which is 50 connected therewith and with a hanger 61 on the trap plate.

A lip 64 projects laterally from the arm 55 through an arcuatile slot 66 in the side of a coin chute and is adapted for travel 55 through the chute channel when the lever arm is rocked downwardly by actuation of the plunger.

The lever 51 has a depending arm 68 and connected with said arm, and with a lip 69 60 on the tooth 49 of the toggle lever, is a spring 70 whereby the toggle lever is returned to initial position after each actuation.

On the rear arm of the lever 51 is a finger 65 72 which projects into the chute channel and

has a downwardly and outwardly inclined lip 73 thereon between which and the head 48 on the toggle lever, a coin is adapted to seat after being inserted into the mouth of the chute.

Pivottally connected with the forward end of the lever 51 is a link 74 which projects up through an opening 75 in the trap plate and is adapted for projection into the slots 24 in the lower drum member when the lever 51 is rocked by the lowering of a coin against the finger 72, thereby holding the drum in a delivery position and preventing further revolution thereof until an article has been delivered through the trap to a purchaser.

The coin chute may be of any ordinary construction, having a slot 76 at the front of the machine and having a lateral opening 77 through which a coin of less than a proper diameter may be thrust by the tension of a spring 78, the head 79 of which projects through an opening 80 in the side of the chute opposite opening 77 so that as small coins pass down the chute they are thrust laterally and fall through the opening instead of passing to the trap position.

The opening 27 in the trap plate is closed by a cap 82 having a leaf 83 hinged to a pin 84 carried by ears 85 that depend from the trap plate, and having a cutout portion 86 for latching over a spring lip 87 on the trap plate. The cap is also preferably provided with a handle 89 by which it may be opened when articles are to be placed in the carrying drum.

The articles when released from the trap plate drop into a vertical chute 90 which extends through the bottom of the casing 1 and has a bottom tray 91 provided with a cushion 92 for receiving the can, or other article, and preventing its breaking when stopped by the tray.

In order to hold the articles in the tray until removed by the purchaser, I provide a depending chain, or the like, 93, which hangs in front of the opening 94 in the chute 90, and is adapted to catch the cans or articles should they tip outwardly after striking the tray. It is apparent that the chain may be easily swung out of the way to allow 115 the purchaser to remove the article.

In using the machine, presuming the parts to be assembled as described, and the drum filled with the articles indicated by the tickets in the holders 34, a purchaser desiring an article indicated by one of the tickets revolves the drum by manipulating the handle 18 until the pointer 33 for the article designated by the ticket in the holder points opposite the pointer on the stationary trap plate. With the pointers in this position, the can or article desired is immediately above the delivery opening in the trap plate and supported on the cap 37, the cans or articles all being supported by the trap plate 130

or caps and sliding over the top of the plate when the drum is revolved. The purchaser then drops the proper coin into the chute and the coin traveling down the inclined 5 channel stops against the head 48 on the toggle lever and rests on the lip 72 of the lever 51. The purchaser then pushes inwardly on the plunger 58, rocking the bell crank lever 56 against the tension of its spring so that the 10 lip 64 on said lever is moved downwardly into contact with the top of the coin and pushes the coin down against the toggle arm and lip 72, rocking the lever 51 so that the lower end of the toggle is released and the 15 link 75 is pushed upwardly into a slot in the lower drum member to prevent the drum from being revolved during the delivery operation. As the coin is moved downwardly it pushes outwardly on the toggle 20 head breaking the toggle so that the cap 37 is lowered by the positive actuation of the toggle and also by the weight of the article carried thereon, the article dropping through the trap and being delivered to the tray at 25 the bottom of the delivery chute. As soon as the delivery is made, the spring 60 rocks the bell crank lever back to its original position, the inclined head of the outer lever arm straightening the toggle to move the 30 cap back into its opening, and the head 48 tensioning the spring 70 to close the lever 51, so that it holds the toggle in straightened position, thereby preventing its breaking under weight of an article moved thereover 35 when the drum is again revolved.

It is apparent that with this mechanism a purchaser may select any desired article and move same to a vending position after which he may secure the article by placing a coin 40 in the machine and operating the plunger.

The drum may be refilled by removing the door in the front of the case and projecting the cans or other articles up through the feed opening 27 after the cap 82 has been 45 opened.

Having thus described my invention, what I claim as new therein and desire to secure by Letters-Patent, is:—

1. A vending machine comprising a casing, a trap plate mounted in the casing and provided with an opening, a trap member 50 adapted for closing the opening, a drum rev-

elable above the trap plate and adapted for pushing the articles over the plate and onto the trap member, mechanism operable from the exterior of the casing for controlling the trap member, and means also operable by said mechanism for locking the drum. 55

2. A vending machine comprising a casing, a trap plate mounted in the casing and provided with an opening, a drum adapted 60 for moving articles over the plate and onto the member, said drum comprising spaced disks having registering apertures, one of said members being provided with slots, mechanism operable from the exterior of the casing for releasing said trap, and a link 65 operable from said mechanism and adapted for projection into the drum slots, for the purpose set forth. 70

3. A vending machine comprising a casing, a horizontal trap plate mounted in the casing and provided with a delivery opening, a trap member hingedly connected with the plate and adapted for closing the opening, means for holding the trap member in closed position, mechanism operable from the exterior of the machine for actuating the trap holding means, and a stop member 75 adapted for actuation by said mechanism to hold the drum when the trap member is actuated. 80

4. A vending machine comprising a trap plate, having an opening, a trap member for closing the opening, means for moving articles over the trap member, a toggle connected with the trap member, and lever mechanism operable from the exterior of the machine for breaking the toggle. 85

5. A vending machine comprising a trap 90 plate having an opening therein, a trap member for closing the opening, means for moving articles over the trap member, a toggle connected with the trap member, a lever having a latch tooth for holding the toggle 95 in a straightened position, and a plunger mechanism adapted for actuating the latch member and toggle.

In testimony whereof I affix my signature in presence of two witnesses.

CHARLES A. MELCHERT.
